United States Patent Office

Des. 198,522
Patented June 30, 1964

198,522

KNOB

La Verne E. Clayton, Rockford, Ill., assignor to Amerock
Corporation, Rockford, Ill., a corporation of Illinois

Filed Dec. 13, 1962, Ser. No. 72,840

Term of patent 14 years

(Cl. D10—8)

FIGURE 1 is a front elevational view of a knob embodying my new design.

FIG. 2 is a side view of the knob.

FIG. 3 is a perspective view of the knob.

FIG. 4 is a fragmentary sectional view taken along the line 4—4 in FIG. 1.

I claim:

The ornamental design for a knob, substantially as shown.
